COTTON STRIPPING MACHINE

Bill I. Pacha, Holland, Tex.

Application June 8, 1953, Serial No. 360,075

3 Claims. (Cl. 56—33)

This invention relates to new and useful improvements in cotton harvesters and the primary object of the present invention is to provide novel and improved means for effectively combing cotton and for removing the weeds from the cotton during the combing operation.

Another important object of the present invention is to provide a cotton stripping and combing machine involving oppositely rotating power driven stripper rollers each of which supports a plurality of radially slidable combing fingers that ride against a stationary cam member positioned in each roller so as to project certain of the fingers outwardly from their supporting roller and toward each other during rotation of the roller for the purpose of effectively combing and stripping cotton.

A further object of the present invention is to provide a cotton combing and stripping machine consisting of a lower pair of stripper rollers which are located below the combing rollers and which rotate in relatively opposite directions and oppositely to the combing rollers for the purpose of pulling weeds, twigs or the like from cotton being handled by the combing rollers.

A further object of the present invention is to provide a cotton combing machine of the aforementioned character involving a pair of conical rollers which may replace the combing rollers and a drive connection between the combing and stripping rollers so that the combing rollers replaced by the stripping rollers and a lower set of stripping rollers will rotate in a similar direction to convert the device from a cotton combing machine to a corn puller, in a convenient manner.

A still further aim of the present invention is to provide a cotton stripping and combing machine that is extremely simple and practical in construction, strong and reliable in use, efficient and durable in operation, inexpensive to manufacture, and otherwise well adapted for the purposes for which the same is intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a top plan view of the present invention operatively mounted on a tractor and coupled to a collecting wagon;

Figure 2 is a longitudinal vertical sectional view taken substantially on the plane of broken section line 2—2 of Figure 1;

Figure 3 is an enlarged fragmentary longitudinal vertical sectional view taken substantially on the plane of section line 3—3 of Figure 1;

Figure 4 is an enlarged fragmentary transverse sectional view taken substantially on the plane of section line 4—4 of Figure 1 with the rods omitted;

Figure 5 is an enlarged fragmentary transverse sectional view taken substantially on the plane of section line 5—5 of Figure 1;

Figure 6 is an enlarged detail sectional view taken substantially on the plane of section line 6—6 of Figure 3;

Figure 7 is a fragmentary longitudinal sectional view of one of the combing rollers taken substantially on the plane of section line 7—7 of Figure 6 with one row of combing fingers removed for the purpose of illustration;

Figure 8 is a view similar to Figure 5 but showing the invention in slightly modified form; and

Figure 9 is a fragmentary top plan view showing the two sets of rollers employed in conjunction with the modified form of the invention disclosed in Figure 8.

Referring now to the drawings in detail, wherein for

2

the purpose of illustration, there is disclosed a preferred embodiment of the present invention, the numeral 10 represents a slide housing having its rear end suitably secured to a wheeled support 12 which is coupled to a collector, such as a wagon 14, by a tow bar 16. The forward open end of the housing 10 fixedly supports ground shoes or skids 18 that will ride upon the ground as the housing is moved forwardly by a tractor 20 to which the support 12 and housing 10 are connected by a rigid framework 22.

The inner side walls 24 and 26 of the housing 10 fixedly support horizontal arms 28 and 30 having holding bearings 32 and 34 secured thereto. The supporting shafts 36 and 38 of a pair of side-by-side, hollow cylindrical, combining rollers 40 and 42 are held in the bearings 32 and 34 by set screws or the like 44 and 46 so that the rollers 40 and 42 may rotate on shafts 36 and 38.

Each of the rollers 40 and 42 is provided with circumferentially spaced, longitudinally extending rows of apertures 48 and bushings 49 are secured to the rollers in association with each of the apertures 48 such that the bores of the bushings are in radial alignment therewith for slidably receiving the rows of combing fingers or short rods 50. The inner ends of the fingers 50 are enlarged to form seats 51 for the inner ends of coil springs 52 that embrace the fingers 50. The springs 52 are biased between the inner peripheries of the rollers 40 and 42 and the seat-forming ends 51 to yieldingly urge the fingers 50 radially inwardly of the outer peripheries of their supporting rollers.

The intermediate portions of the shafts 36 and 38 are formed with bar cams or elongated cam members 54 that extend longitudinally of the rollers and within the rollers. The lobes 56 of the cam members 54 are disposed in a common plane and extend toward each other from the axes of the shafts 36 and 38, so that as the cylindrical rollers 40 and 42 rotate, the seat-forming ends 51 of the rows of fingers of the rollers closest together will ride against the lobes 56 to project these fingers radially outwardly from the rollers, as shown in Figures 1 and 7.

In order that the fingers projected from one roller will not engage the fingers projected from the other roller, the rows of finger-accommodating apertures 48 in one roller are staggered relative to the rows of apertures in the other roller, or else, the rollers are longitudinally offset from each other, and through this construction, the projected fingers of one roller will be interdigitated with the projected fingers of the other roller.

Means is provided for rotating the rollers 40 and 42 in relatively opposite directions so that roller 40 will rotate clockwise and roller 42 will rotate counter-clockwise when viewing these rollers from the rear ends thereof, as shown in Figure 5. This roller rotating means consists of a longitudinal driven shaft 58 rotatably supported by support 12 and having a drive connection 60 with the power take-off shaft 62 of the tractor 20. A suitable reversing gear mechanism 64 is coupled to the sections of shaft 58 and actuated by a hand lever 66 so that shaft 58 may rotate either clockwise or anti-clockwise for a purpose presently to be described.

The forward end of shaft 58 fixedly supports a sprocket 68 that is connected to a sprocket 70 fixed to the rear end of roller 40 by an endless sprocket chain 72. The upper flight of chain 72 engages the bottom portion of a sprocket 74 fixed to the rear end of roller 42.

A lower pair of side-by-side cylindrical stripping rollers 76 and 78 underlie the combing rollers 40 and 42, and are disposed closer together than are the combing rollers. The rollers 76 and 78 have supporting shafts 80 and 82 which are held in bearings 84 and 86 carried by arms 88 and 90. The arms 88 and 90 are fixed to the side walls 24 and 26 of housing 10 under the arms 28 and 30. The rollers 76 and 78 are rotated in relatively opposite directions and opposite to the rollers 40 and 42 to pull weeds and the like from cotton being combed by the rollers 40 and 42.

Framework 22 rotatably supports a shaft 92 which underlies shaft 58. A sprocket 94 fixed to shaft 92 is connected to a sprocket 96 fixed to shaft 58 by an endless sprocket chain 98 so that shaft 92 will be driven by shafts

62 and 58. Shaft 92 fixedly supports a second sprocket 100 that is connected to a sprocket 102 fixed to the rear end of roller 78 by an endless sprocket chain 104 to cause roller 78 to rotate in a similar direction as shafts 58 and 92.

An idler sprocket 106, suitably carried by housing 10, engages a sprocket chain 108 that extends about a second sprocket 110 fixed to the rear end of roller 78 and the upper flight of chain 108 engages the bottom portion of a sprocket 112 fixed to the rear end of roller 76, so that rollers 76 and 78 will be driven, as shown by arrows in Figure 5, to pull weeds, sticks or the like downwardly from cotton engaged between rollers 40 and 42.

Longitudinal conveyor belts 114 and 116 are carried by rollers 118 and 120 mounted on the side walls 24 and 26 of the housing 10. Belt 114 is disposed between roller 40 and side wall 24 and belt 116 is disposed between roller 42 and side wall 26, as shown in Figure 4, so that cotton leaving the rollers 40 and 42 will pass onto the belts 114 and 116. The rollers 118, 120 at one end of each of the belts 114 and 116 are power driven by suitable means, such as by power take-off shafts 62, so that the upper flights of these belts will move rearwardly to conduct cotton to the rear of the housing where the cotton will drop onto a transverse conveyor 122 suitably mounted upon the support 12.

Conveyor 122 comprises a pair of rollers 124 with central peripheral V-shaped grooves 126 over which there is engaged an endless conveyor belt 128 that will form a transverse trough. One of the rollers 124 is power driven by suitable means operatively connected to the power take-off shaft of the tractor to move the belt 128 toward the inlet 130 of a blower unit 132 that is supported on support 12. The outlet 134 of unit 132 extends to the wagon 14 to direct cotton leaving conveyor 122 and entering the inlet 130, into the wagon 14.

Figures 8 and 9 illustrate the present invention in modified form whereby the device may be employed for pulling corn. In this embodiment, the rollers 40 and 42 are replaced by conical spirally ribbed rollers 40a and 42a whose rear ends carry sprockets 70a and 74a that engage the sprocket chain 72a in the same manner described in conjunction with Figure 5, however, lever 66 is actuated to drive shaft 58 oppositely from the direction of drive utilized with the rollers 40 and 42, previously described, and hence, rollers 40a and 42a will rotate toward each other.

The sprocket 100a on shaft 92a engages an endless sprocket chain 104a that extends about the sprocket 112a at the rear end of roller 76a and the lower flight of chain 104a engages over the sprocket 110a at the rear end of roller 78a so that rollers 76a and 78a now rotate downwardly toward each other as do the rollers 40a and 42a.

In practical use of the present invention, the tractor 20 is moved forwardly and cotton plants are engaged between the rollers 40 and 42 so that as the rollers 40 and 42 are driven, the projected fingers 50, which extend between the rollers 40 and 42, will strip the cotton from the plants and effect a combing of the cotton. The cotton will be lifted by these rollers 40 and 42 and dropped onto the belts 114 and 116 where the cotton is moved rearwardly onto the conveyor 122. The cotton is drawn from the conveyor 122 by the unit 132 and directed into the wagon 14. During the combing of the cotton by the rollers 40 and 42, the rollers 76 and 78 will pull weeds, twigs and the like downwardly, and drop this foreign matter onto the ground.

In order to employ the device as a corn puller, the rollers 40 and 42 are replaced by the rollers 40a and 42a and the rollers 76a and 78a are driven in the manner described in conjunction with Figure 8.

What is claimed as new is as follows:

1. In a cotton harvester including an elongated slide housing having an open forward end to accommodate cotton plants, a pair of side-by-side hollow combing rollers rotatably supported by and mounted in said housing behind the open forward end of said housing, means operatively connected to said rollers for rotating the rollers in relatively opposite directions, each of said rollers having circumferentially spaced longitudinally extending rows of apertures, a sliding combing finger received in each aperture of each roller, a pair of cam members each disposed in one of said rollers and held stationary on the housing in spaced parallel relationship, each cam member projecting axially through an associated roller, said cam mem-

bers each having a lobe, said lobes extending toward each other and lying in a common plane, and means mounted on and within said rollers engaged with each finger and yieldingly urging the finger radially inwardly of the outer periphery of the rollers into engagement with an associated cam lobe, whereby rotation of said rollers will effect sequential projection of the rows of fingers through their accommodating apertures.

2. In a cotton harvester including an elongated slide housing having an open forward end to accommodate cotton plants, a pair of side-by-side hollow combing rollers rotatably supported by and mounted in said housing behind the open forward end of said housing, means operatively connected to said rollers for rotating the rollers in relatively opposite directions, each of said rollers having circumferentially spaced longitudinally extending rows of apertures, a sliding combing finger received in each aperture of each roller, a pair of cam members each disposed in one of said rollers and held stationary on the housing in spaced parallel relationship, each cam member projecting axially through an associated roller, said cam members each having a lobe, said lobes extending toward each other and lying in a common plane, and means mounted on and within said rollers engaged with each finger and yieldingly urging the finger radially inwardly of the outer periphery of the rollers into engagement with an associated cam lobe, whereby rotation of said rollers will effect sequential projection of the rows of fingers through their accommodating apertures, the rows of apertures in one roller being staggered with respect to the apertures in the other roller so that the fingers projecting radially outwardly on one roller will be interdigitated with the fingers projecting radially outwardly from the other roller.

3. In a cotton harvester including an elongated slide housing having an open forward end to accommodate cotton plants, a pair of side-by-side hollow combing rollers rotatably supported by and mounted in said housing behind the open forward end of said housing, means operatively connected to said rollers for rotating the rollers in relatively opposite directions, each of said rollers having circumferentially spaced longitudinally extending rows of apertures, a sliding combing finger received in each aperture of each roller, a pair of cam members each disposed in one of said rollers and held stationary on the housing in spaced parallel relationship, each cam member projecting axially through an associated roller, said cam members each having a lobe, said lobes extending toward each other and lying in a common plane, and means mounted on and within said rollers engaged with each finger and yieldingly urging the finger radially inwardly of the outer periphery of the rollers into engagement with an associated cam lobe, whereby rotation of said rollers will effect sequential projection of the rows of fingers through their accommodating apertures, a lower pair of side stripper rollers and supported by and mounted in said housing and underlying the combing rollers, means operatively connected to the stripper rollers for rotating the same oppositely relative to each other and to the combing rollers, whereby weeds and plants gripped by the combing rollers will be pulled therefrom by the stripping rollers.
